Inventor:

A. KVAAL

by

Langner, Barry, Land & Langner,
Att'ys.

UNITED STATES PATENT OFFICE.

ALBERT KVAAL, OF CHRISTIANIA, NORWAY.

CONNECTION PIECE FOR CABLE HEADS.

Application filed December 13, 1924. Serial No. 755,757.

To all whom it may concern:

Be it known that I, ALBERT KVAAL, a subject of the King of Norway, residing at Universitetsgaten 11, Christiania, Norway, have invented certain new and useful Improvements in Connection Pieces for Cable Heads; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

20 This invention affords a connecting means for wires and the like, enabling the ready quick and secure electrical connection between two wires.

25 At the points where telephone and telegraph cables are divided into single wires the several wires of a cable are soldered to connection pieces to which connection pieces the several wires are again connected. This invention provides an improved connecting means.

30 One embodiment of the invention is shown merely by way of illustration in the accompanying drawings wherein Fig. 1 is a longitudinal part sectional view of a connection piece positioned in an insulating block, and

35 Fig. 2 is an elevation of the connecting element, parts being shown in section.

40 In the form illustrated the strip-like connection piece 1 is mounted in a narrow aperture 3 of elongated rectangular cross section formed in an insulating block 2 and is fastened therein against upward withdrawal by having its lower end twisted about its axis as illustrated in Fig. 1. The aperture 3 terminates on the front side of the insulating block 2 in an enlarged rectangular recess 4 which receives a fastening device for a single wire. This fastening device comprises a nut 5 which is fitted between portions 6 and 6' which portions engage the nut on all of its four sides. The

nut has a threaded aperture 8 which corresponds with an aperture 7 in one of the 50 bent members 6 of the strip 1, when the nut is in position in the strip. A clamping screw 9 for the single wire 10 is introduced into the nut through the aperture 7 in the strip. The lower part 6 of the strip 1 55 rests on the bottom of the recess 4 when in position in the block as shown in Fig. 1.

As described above the connection strip is bent so as to form a rectangular clamp for the nut as two complete sides 6, 6 and 60 two approximately half sides 6', 6' so that the nut when mounted in the clamp has its vertical axis in line with the axis of the connection strip 1.

Having described one operative embodiment of the invention, I now claim:

1. A connection piece for cable heads, comprising, a metallic strip, one end of the strip having receiving means integral therewith to receive a clamping screw and nut 70 for a continuation wire, said receiving means including, two spaced parallel portions of the strip running parallel to the axis of the strip, and two spaced parallel portions of the strip running at right 75 angles to the axis of the strip, and a receiving aperture for the clamping screw.

2. A connection piece for cable heads, comprising, a metallic strip, one end of the strip having receiving means integral therewith to receive a clamping screw and nut 80 for a continuation wire, said receiving means including, two spaced parallel portions of the strip running parallel to the axis of the strip, and two spaced parallel 85 portions of the strip running at right angles to the axis of the strip, and a receiving aperture for the clamping screw in line with the axis of the strip.

In testimony that I claim the foregoing 90 as my invention, I have signed my name in presence of two subscribing witnesses.

ALBERT KVAAL.

Witnesses:

JENS M. LUND,
MAGNUS BUGGE.
